US00D422281S

United States Patent

[19]

Tang

[11] Patent Number: Des. 422,281

[45] Date of Patent: ** Apr. 4, 2000

[54] MICROPHONE

D. 317,472 6/1991 Sasaki et al. .... D14/225 X
5,706,359 1/1998 Chang ..... 387/168 X[75] Inventor: **Shih-Chun Tang**, Tainan, Taiwan

OTHER PUBLICATIONS

[73] Assignee: **Chiayu Electronics Co., Ltd.**, Chiayi,
TaiwanTarg and Dinner, p. 101, Model 515SA, microphone, Apr.
1970.[**] Term: **14 Years**

Primary Examiner—Nanda Bondade

[21] Appl. No.: **29/099,991**

[57] CLAIM

[22] Filed: **Feb. 1, 1999**The ornamental design for microphone, as shown and
described.[51] LOC (6) Cl. **14-01**

DESCRIPTION

[52] U.S. Cl. .... **D14/228**FIG. 1 is a perspective view of microphone showing my
design;[58] Field of Search D14/206, 223,
D14/225-229; 181/158, 242; 379/430, 431;
381/91, 168, 169, 183

FIG. 2 is a front elevational view thereof;
